GEORGE G. REED, OF HOLYOKE, MASSACHUSETTS, ASSIGNOR OF ONE-HALF TO
NATHAN P. AVERY, OF HOLYOKE, MASSACHUSETTS.

MOISTENER FOR DENTAL TOOLS.

1,005,468.

Specification of Letters Patent. Patented Oct. 10, 1911.

Application filed December 21, 1910. Serial No. 598,541.

To all whom it may concern:

Be it known that I, GEORGE G. REED, a citizen of the United States of America, residing at Holyoke, in the county of 5 Hampden and State of Massachusetts, have invented a new and useful Moistener for Dental Tools, of which the following is a specification.

My invention relates to improvements in 10 tool-holders for dentists' use, and more particularly to the guards with which such holders are provided for the abrading, polishing and cutting stones and disks driven by dental-engines, and consists of 15 certain peculiar means applied to such a guard for moistening the rotary abrading, polishing or cutting member or tool, as hereinafter set forth.

While using the above-mentioned rotary 20 members or tools it is necessary that they be kept moist, like most other grinding and cutting tools which revolve at a high rate of speed, and heretofore it has been the custom to dip them frequently into 25 water or some other fluid for that purpose. These repeated dippings consume considerable time and involve some effort on the part of the operator, and very often the tools are inadequately moistened even when 30 quite frequently immersed in the fluid. The dipping of the tools into the fluid also washes away the accumulation of particles thereon from the teeth and from the tools themselves.

35 The object of my invention is to produce convenient and effectual means for moistening the tools automatically and at the same time cleaning them by removing the accumulating particles therefrom, and thus

40 economizing time and energy of the operator which would otherwise be wasted, such means being readily attached to or incorporated with dental-engine tool guards in common use.

45 Other objects will appear in the course of the following description.

I attain these objects by the means illustrated in the accompanying drawings, in which—

50 Figure 1 is a side elevation of a practical form of my invention, showing the same applied to a dental-engine hand-piece; Fig. 2, a front end elevation of the parts illustrated in the preceding view; Fig. 3, a front end 55 elevation of the guard and moistener, de-

tached; Fig. 4, a top plan of the guard and its sleeve, showing the holder for the absorbent material without the latter; Fig. 5, a front end elevation of a slightly modified form of guard and moistener, and, Fig. 6, a similar view excepting that the absorbent material is omitted. 60

Similar figures refer to similar parts throughout the several views.

Before proceeding to describe my invention in detail and as represented in the drawings, attention is called to the fact that the same consists of means arranged and adapted to retain absorbent material, such as sponge, cotton, wood-pulp, cork, 65 leather, fabric of any suitable kind, or a brush, in contact with the tool which it is desired to moisten, such means being attached to or forming a part of the guard for such tool. 70

Certain changes in the shape, size and construction of my invention may be made without departing from the nature of the same or exceeding the scope of my claims. 75

Referring now to the drawings, it will be 80 observed that I have illustrated in the first view a dental-engine handpiece 1, a guard 2 having a sleeve 3 by means of which said guard is attached to said handpiece, and a tool 4 secured by a screw 5 to the driving 85 spindle, which latter is not shown. With the exception of the guard 2, these parts and members are all of common and well-known construction and operate in the usual manner. The guard 2 has a rim 6 which is cut 90 away at 7 to accommodate the tool 4, as is usual. In the examples shown, the guard and sleeve are integral, but they need not necessarily be so.

The guard 2 illustrated in the first four 95 views has a second opening 8 in its rim 6, and one or more wires or rods 9 (two in the present case) are arranged over such opening with their ends fastened to such rim. These rods together with the supporting 100 parts therefor of the guard constitute a holder for a piece of sponge or other absorbent material 10. The absorbent material 10 is forced in between the rods 9 until it is in a position to bear on the periphery of 105 the tool 4, and against one or both sides of said tool adjacent to such periphery, if desired.

In practice, the absorbent material 10 is saturated and moisture therefrom is com- 110

municated or supplied constantly to the revolving tool 4, and the particles produced by such tool are wiped off on said material, without any attention on the part of the operator. One saturation of the absorbent material is sufficient to last some little time. When the absorbent material becomes soiled it can be easily removed from and a fresh piece inserted in the holder, and, of course, 10 the change is made before employing the moistener in connection with a new case.

The moistener employed in the last two views comprises a single rod or hook 11 within the rim 6 of the guard 2, the latter 15 including said rim being elongated a little to make room for such hook and for the absorbent material 10 which the former is designed to secure in place as the holder of this moistener. Here the absorbent material 20 10 is forced into place over the hook 11, or the latter is sprung outwardly far enough to enable such material to be impaled thereon. The second moistener functions in precisely the same way as does the first.

25 What I claim as my invention, and desire to secure by Letters Patent, is—

1. The combination, in a moistener for dental engines, with a dental-engine hand-piece, and a rotary tool adapted to be supported thereby, of a guard for such tool,

such guard consisting in part of a rim attachable to said handpiece, and absorbent-material securing means forming a part of that portion of said guard that covers the working portion of said tool. 35

2. The combination, in a moistener for dental-engines, with a dental-engine hand-piece, and a rotary tool adapted to be supported thereby, of a guard consisting in part of a recessed rim attachable to said hand-piece, a securing member bridging the recess in said rim, and a piece of absorbent material inserted in the recessed portion of said rim and projecting inward against said tool, such absorbent material being held in 40 45 place by said securing member.

3. The combination, in a moistener for dental engines, with a dental-engine hand-piece, and a rotary tool adapted to be supported thereby, of a guard for such tool, 50 such guard consisting in part of a rim attachable to said handpiece, and absorbent-material securing means in that portion of said guard that covers the working portion of said tool.
